THOMAS E. CLARK, OF DETROIT, MICHIGAN, ASSIGNOR TO CONTINUOUS TRAIN CONTROL CORPORATION, OF DETROIT, MICHIGAN, A CORPORATION OF MICHIGAN.

SAFETY INSTALLATION FOR GRADE CROSSINGS.

Application filed March 25, 1927. Serial No. 178,240.

- This invention relates to means designed to reduce the number of accidents which occur at the crossings of highways and railway tracks because the drivers of automobiles 5 do not realize the approach of trains, and its object is to provide means at such crossings to impart proper electric signals to the automobiles and to provide means on the automobiles to respond to such signals.
- 10 This invention consists in an electric installation positioned at a railway and highway crossing, and means whereby such installation is caused to operate upon the approach of a railway train, and of a high-frequency 15 current transmitting means positioned a proper distance from such crossing and preferably embedded in the roadway.
- It also consists in signals at points on the highway a distance from the crossing to 20 designate the approach of trains.
- It also consists of electro-responsive means adapted to be mounted on automotive vehicles, which, when said current transmitting means along the highway are functioning, 25 will respond thereto either by causing a signal on the vehicle to be energized, or the circuit for the ignition current of the automobile engine to be opened, or the automobile's brakes to be applied, or to cause either two or 30 all of these acts to occur simultaneously.
- It also consists of means for notifying the engineer of the approaching train, either by audible or visible signal or both, that he is approaching such a crossing.
- 35 It further consists in the details of construction illustrated in the accompanying drawings and particularly pointed out in the claims.
- In the accompanying drawings, Fig. 1 is a 40 diagram of an electric trackway installation for controlling the operation of automobiles at crossings; Fig. 2 is a diagram of an automobile installation adapted to respond thereto; Fig. 3 is a diagram of another automobile 45 installation; Fig. 4 is a diagram of a modified form of trackway installation; Fig. 5 is a diagram of a locomotive installation adapted to respond thereto; and Fig. 6 is a perspective view showing conductor wires embedded in a roadway slab.

Similar reference characters refer to like parts throughout the several views.

While the word "locomotive" is used in this application to designate the vehicle on the

track rails, it should be understood that this 55 term is intended to include self-propelling rail-vehicles of all kinds.

The trackway installation.

In the drawings, the pairs of rails 1 and 2, 3 and 4 of a double track are indicated as divided into blocks by means of insulations 5 and to each block at its entrance end is connected a track-battery 6, and adjacent the crossing highway is a control relay 7-8. 65 The control current is derived directly from an electron tube 9 whose filament is heated by current from the battery 10 when either of the tracks of the adjacent block are occupied. In the present case a train T occupies the east-bound track, resulting in the short-circuiting of the relay 7. Current now passes from the battery 10 over wires 12 and 13, armature 14, wires 15 and 16, filament of tube 9 and wires 17 and 18 to the battery. If 70 the other track were occupied, the armature 19 of relay 8 would have closed this circuit.

The plate circuit of this tube 9 includes the battery 20, wire 21, plate coil 22, wire 23 to the plate, and on the other side, the wires 24, 25 and 17 to the filament. The grid coil 26 connects to the wire 25 and to the grid by the wire 27, while it connects to the ends of the plate coil 22 by means of condensers 28.

The high-frequency current output coil 30 85 connects to the roadside inductor loop 38 by means of wire 32, primary winding 33 of a signal-control inductance, and wires 34 and 35, while it connects to the other roadside inductor loop 39 by means of the wire 36, a condenser 37 being installed to tune the output 90 circuit. The loops are connected by wire 31 to complete the circuit. Whenever, therefore, either of the tracks is occupied, high-frequency current will pass to the inductor 95 loops 38 and 39, one at each side of the railway track.

Signal lamps along the roadway and railway tracks are controlled by a relay 41 having an armature 42. This relay is energized 100 by induced current in the secondary winding 43 when the primary winding 33 receives current, this current being rectified by the radio-frequency rectifier 44 of any desired construction, the relay being connected to the winding 43 by wire 45 on one side and the wires 46 and 47 and the rectifier 44 on the other. When this relay is energized, direct current

flows from battery 10 over wires 12, 13, armature 14, 16 and 49, armature 42 and wire 50 to the wire 52 which connects directly to the safety signals 53 and to the danger signal 54 by wire 55 to the danger signal 56, and by wire 57 to the safety signal 58. These signals may be lamps or bells or any other proper devices. The other side of the battery connects to the main return wire 59 by wire 60, 10 the signals 53 and 58 connecting directly to this wire 59, while the signal 56 connects thereto by the wire 62, and the signal 54 by wire 63. Should the west-bound track be occupied, relay 8 would be de-energized, and 15 armature 19 would close these lamp circuits.

If the electron tube or the circuits or parts connected thereto should be inoperative, the relay 41 is de-energized and current passes from armature 42 over wire 64 to the wire 65, 20 which connects directly to the "danger" signals 66, 67 and 68, the wire 64 extending to danger signal 69. The returns from these lamps to the wire 59 are clearly shown in the diagram. These signals therefore indicate to the automobile driver whether or not 25 a train is approaching and to the locomotive drivers that the installation is or is not functioning according as the signals 53 and 58 or 66 and 68 function as the locomotive passes 30 an insulation 5. But should the installation cease to function, the lamps 67 and 69 would receive current and thus constitute a permanent warning to automobile drivers. These lamps or signals may be sufficiently different 35 from the lamps 54 and 56 to accomplish this purpose. The signals along the track and the signals 54 and 56 are preferably lamps, the signals 53 and 58 being green and the others red. When the engineer sees the green lamp 40 he knows the entire installation is functioning but the red lamp notifies him that the loops 38 and 39 are not energized. The signals 67 and 69 should be very noticeable as they too function when the loops are dead.

45 *The automobile installation.*

Mounted on the automobile is an auxiliary plate battery 72 which connects to the plate of an electron tube 73 by a wire 71, but it is 50 to be understood that this battery may be replaced by any other desirable current source, such as a small generator driven by the automobile engine. The ordinary storage battery 74 connects to the wire 75 by means 55 of a starting switch 76, and then to the horn-button 77 by wire 78, the button connecting to the horn 79 by wire 80. The filament of the tube connects to the wire 75 by wire 82 and is grounded by wire 83. Plate current 60 normally passes to energized relay 84, wire 85, armature 86, wire 87, 75 and 82 to the filament. If this circuit should be broken and relay 84 become de-energized and armature 86 dropped, key 88 may be depressed, completing the circuit by way of wire 78, after 65

which the relay will pick up its armature and close its normal circuit.

When the automobile passes over an energized loop 38 or 39, electro-magnetic flux is 70 picked up by the receptor coil 90 which connects to the filament of the tube 73 by means of wires 91 and 83 and to the grid by wires 92 and 93, connected by the condenser 94 and grid leak 95, the wires 91 and 92 being connected by an adjustable condenser 96 by 75 means of which this loop may be tuned to the frequency of the current in the loops 38 and 39. With the arrangement of the parts shown in Fig. 2 a negative charge is accumulated on the grid as the result of the reception 80 of current by the receptor coil 90, so that it interferes materially with the passage of the plate current, sufficiently so as to prevent the energization of relay 84 which drops its armature.

Current now flows from battery 74 over switch 76, wires 75 and 87, armature 86 and wires 97 and 80 to the horn 79 which sounds and signals to the driver the approach of a train on one of the tracks. The horn will 90 continue to sound until the resetting key 88 is depressed. The loops 38 and 39 and the roadside wires 31 and 35 may be covered with an insulation 99 which will not be affected by the concrete of the roadway 100 in 95 which these wires may be embedded.

In Fig. 3, a more elaborate automobile installation is shown diagrammatically. The relay 84 is provided with a second armature 101 which normally closes a circuit to the spark coil 102 from wires 75 and 87 over wire 103, and opens this circuit when the relay 84 is de-energized. A small dash pot 104 may be connected to armature 101 to steady its movement.

Where such construction is possible or desirable, an electrically operated brake may be provided to stop the automobile when relay 84 is de-energized. The rods 106 extending from the brake mechanism connect to arms 107 on the shafts 108, which also have arms 109 at their inner ends. Links 110 connect these arms to a cross bar 112 attached to the core 113 which extends through the solenoid 114. A wire 115 connects to the armature 110 in dropped position while a wire 116 connects to the wire 83 and to the ground. The details of such a construction are well known.

110 *Trackway circuits.*

In Figure 5, the relay 41 is provided with additional armatures 120 and 121 which close the circuit between the output coil 30 and the wires 122 and 123 leading to the trackway 125 wires 124 and 125 which connect to the primary windings 126 of transformers 127 and 128, the secondary windings 129 of these transformers connecting to the rails 1-2 and 3-4 respectively. When high-frequency 130

electro-magnetic flux occurs in the loops 38 and 39, similar flux will be present in the rails.

Locomotive installation.

5 The receptor coil 131 (Fig. 5) is preferably mounted on the leading truck of the locomotive near the rails so as to pass through the energized fields of greatest electro-magnetic flux around the rails. This installation comprises two electron tubes 132 and 133, whose filament current is derived from a generator G, preferably the headlight generator, and whose plate current is derived from a 10 transformer or dynamotor 134 energized from the generator over wires 135 and 136. The wires 137 and 138 connect the positive side of the dynamotor to the primary winding 139 of the transformer 140, the current 15 passing from this primary winding to the plate of tube 133. A wire 142 extends from wire 137 to relay 143 and wire 144 connects this relay to the plate of tube 132.

The filaments of these tubes are connected 20 to the wire 135 by wires 146 and 147, and to the wire 136 by the wire 148. This provides for the heating current. The plate current passes from the filaments over wires 148 and 136, short wire 149, resistance 150 and wires 30 151 to the dynamotor. The resistance 150 connects to another resistance 153, so that the two may be considered as one of which the coil 150 is the negative end. The resistance of the part 150 may be one thousand ohms 35 and of the part 153 five thousand ohms, which permits only a few milli-amperes of current to pass, a small amount of current however being necessary to impress a negative bias of potential on the goods of the tubes 132 and 133.

A negative bias of potential is therefore impressed upon the grid of tube 133 by reason of the wire 155 engaging the negative resistance 150, this wire connecting to the grid 40 of this tube by wire 156 in which the adjustable condenser 157 is mounted. This negative bias on the grid obstructs to some extent the flow of plate current in this tube, which is a direct current and therefore places a very low load on this tube and also 45 prevents the core of the normal transformer 140 from becoming saturated. The grid of tube 132 connects to this negative resistance 150 by wire 158 and secondary winding 159 of transformer 140 so that a negative bias 50 of potential will also be normally present in this grid, sufficient to so obstruct the flow of plate current in tube 132 and in relay 143 that the armatures 162 and 163 of this relay 55 will normally be down, and current will normally flow from generator G over wire 164 to electro-pneumatic valve 165 which is held closed thereby, wire 166, armature 163 and wire 135 back to the generator.

60 The receptor circuit embodying the col-

ector coil 131 and condenser 157 responds to the electro-magnetic flux around the track rails and an alternating potential is built up in the receptor circuit, and this potential acts on the grid of tube 133 and causes its potential 75 to be first less negative and then more negative and this action causes the current in the plate circuit to increase and decrease in unison with the frequency impressed on the grid circuit. So long as constant direct current passes from filament to plate of tube 133, no current is induced in the secondary winding 159 but when varying potential is induced in the receptor circuit, it changes the bias on the grid of tube 133, the current passing from filament to plate being increased and decreased, resulting in an alternating current being induced in the secondary winding 159.

The positive halves of this alternating current reduce the negative bias of the grid of tube 132 so that current may flow in the plate circuit of that tube and energize relay 143 so that its armatures 162 and 163 are attracted. Armature 162 closes a circuit between wires 135 and 164 through lamp 168 resulting in a visible signal that a highway crossing is less than a block ahead. At the same time, armature 163 opens the circuit to electro-pneumatic valve 165 which results 90 in an alarm whistle 169 blowing, giving an audible signal for the same purpose.

The details of construction and the proportions of resistances, currents and inductances may all be changed by those skilled in 95 the art without departing from the spirit of my invention as set forth in the following claims.

I claim:—

1. In a highway crossing, the combination 105 with railway tracks and a highway crossing them, an electric conductor embedded in the highway, a current source, a transformer for transforming the current into radio-frequency current, a circuit between said source and said transformer, a battery connected to the rails, a relay connected to said rails and adapted to be shunted by an oncoming vehicle to cause the closing of the circuit from the current source to said transformer, and 110 a circuit connecting the transformer to the conductor.

2. In a highway crossing, the combination 115 with railway tracks and a highway crossing them, a conductor embedded in the highway, a current source, a transformer for transforming the current into radio-frequency current, a circuit between said source and said transformer, a source of electric 120 energy connected to the rails, a distance from the highway, a relay connected to said rails a lesser distance from the highway and adapted to be de-energized by an oncoming vehicle passing said battery to cause the closing 125 of the circuit from the current source to said

- transformer, a circuit connecting the transformer to the highway conductor, a roadside signal along the highway a distance from the track, and a circuit between said 5 current source to said signal adapted to be closed when said relay is short circuited.
3. In a highway crossing, the combination with railway tracks and a highway crossing them, a loop embedded in the highway, a current 10 source, a transformer for transforming the current into radio-frequency current, a circuit between said source and said transformer, a battery connected to the rails, a relay connected to said rails and adapted to be 15 shunted by an oncoming train to cause the closing of the circuit from the current source to said transformer, a circuit connecting the transformer to the highway loop, a pair of signals along the highway a distance from 20 the track, and normally open circuits between said current source and said signals, and means to close a selected circuit when said relay is de-energized.
4. In a highway crossing, in combination 25 with track, rails and a conductor embedded in the highway a distance from the rails, an installation for propagating radio-frequency electro-magnetic flux in said conductor and a current source therefor, and means controlled 30 by the presence of a vehicle on the rails within a predetermined distance from said crossing to cause the operation of said propagating means, and a signal along the highway a distance from said crossing, and means to cause 35 the flow of an operating current to said signal when said propagating means becomes operative.
5. In a highway crossing, in combination 40 with track rails and a loop embedded in the highway a distance from the rails, an installation for propagating radio-frequency electro-magnetic flux in said loop and a current source therefor, means controlled by the presence of a vehicle on the rails within a predetermined 45 distance from said crossing to cause the operation of said propagating means, and conductors connecting said propagating means to said track rails.
6. In a highway crossing, in combination 50 with track rails and a loop embedded in the highway a distance from the rails, an installation for propagating electro-magnetic flux in said loop and a current source therefor, means controlled by the presence of a vehicle 55 on the rails within a predetermined distance from said crossing to cause the operation of said propagating means, pairs of signal lamps positioned along the rails and the highway on both sides of the crossing a distance from 60 the crossing, circuits from said current source to each lamp, the circuit to one lamp of each pair being normally open and to the other normally closed, and means to reverse such conditions upon the operation of said propagating means.
7. In combination with a loop in a highway adapted to be charged with electro-magnetic flux, a receptor coil mounted on a vehicle and adapted to be affected by said flux, an audible signal on said vehicle, a current source and a circuit therefrom to said signal, a relay and an electron tube whose plate circuit normally energizes said relay to hold the signal circuit open, and an oscillating circuit between said receptor coil and the grid of said tube to impress a negative bias of potential thereon to interrupt the plate circuit and thereby cause the signal circuit to be closed. 70
8. In combination with a loop in a highway adapted to be charged with electro-magnetic flux, a receptor coil mounted on a vehicle and adapted to be affected by said flux, an audible signal on said vehicle, a current source and a circuit therefrom to said signal, a relay and an electron tube whose plate circuit normally energizes said relay to hold the signal circuit open, an oscillating circuit between said receptor coil and the grid of said tube to impress a negative bias of potential thereon to 75 interrupt the plate circuit and thereby cause the signal circuit to be closed, and means for opening the ignition circuit of the vehicle engine upon the interruption of said plate current. 80
9. In combination with a loop in a highway adapted to be charged with electro-magnetic flux, a receptor coil mounted on a vehicle and adapted to be affected by said flux, an audible signal on said vehicle, a current source and a circuit therefrom to said signal, a relay and an electron tube whose plate circuit normally energizes said relay to hold the signal circuit open, an oscillating circuit between said receptor coil and the grid of said tube to impress a negative bias of potential thereon to 90 interrupt the plate circuit and thereby cause the signal circuit to be closed, and means for opening the ignition circuit of the vehicle engine upon the interruption of said plate current. 95
10. In combination with a loop in a highway adapted to be charged with electro-magnetic flux, a receptor coil mounted on a vehicle and adapted to be charged with electro-motive force when it passes through said flux, an ignition circuit on said vehicle and a source of ignition current therefor, a relay adapted to control said circuit, an electron tube whose plate circuit energizes said relay, and an oscillating circuit connecting to said receptor coil to cause the opening of said ignition circuit when said coil receives electro-motive force from said highway loop. 105
11. In a highway crossing, in combination with track rails and conductors extending along the highway, an installation for propagating electro-magnetic flux in said conductors and a current source therefor, means controlled by the presence of a vehicle on the 115
- 120
- 125

- rails within a predetermined distance from said crossing to cause the operation of said propagating means, signals along the highway, circuits between said current source and said signals, a relay to select said signals and a circuit between said propagating means and said relay embodying a current rectifier.
12. In a highway crossing, in combination with track rails and a loop embedded in the highway a distance from the rails, an installation for propagating electro-magnetic flux in said loop and a current source therefor, means controlled by the presence of a vehicle on the rails within a predetermined distance from said crossing to cause the operation of said propagating means, and conductors connecting said propagating means to said track rails, circuits and transformers connecting said propagating means to the track rails, and means on the vehicle responding to the electro-motive force propagated in said track
- 5

rails to signal the operation of said propagating means.

13. In a highway crossing, in combination with track rails and a loop embedded in the highway a distance from the rails, an installation for propagating electro-magnetic flux in said loop and a current source therefor, means controlled by the presence of a vehicle on the rails within a predetermined distance 25 from said crossing to cause the operation of said propagating means, and conductors connecting said propagating means to said track rails, circuits and transformers connecting said propagating means to the track rails, and 30 means on the vehicle responding to the electro-motive force propagated in said track rails to signal the operation of said propagating means, said means on the vehicle comprising visual and audible signals and a current 35 source to cause their operation.

THOMAS E. CLARK.
